SPIN TOY

Owen D. Kincaid, San Antonio, Tex., assignor to Hoover Products, Inc., Youngstown, Ohio, a corporation of Ohio

Application February 14, 1956, Serial No. 40,172

Term of patent 3½ years

(Cl. D34—15)

I claim:

The ornamental design for a spin toy, as shown.
